UNITED STATES PATENT OFFICE.

GEORGE A. TUTTLE, OF ANATONE, WASHINGTON.

SPRING-OILER.

1,329,864.

Specification of Letters Patent.

Patented Feb. 3, 1920.

Application filed May 21, 1919. Serial No. 298,607.

To all whom it may concern:

Be it known that I, GEORGE A. TUTTLE, a citizen of the United States, and a resident of Anatone, in the county of Asotin and 5 State of Washington, have invented a new and Improved Spring-Oiler, of which the following is a full, clear, and exact description.

This invention relates to an improvement 10 in spring oilers, and aims to more particularly provide a device of this nature in which the individual leaves of a spring may be reached by oil distributed from a common inlet.

15 It is well known that springs at the present time are often broken, due to insufficient lubrication of the individual leaves; and in view of the fact that the oiling of each individual leaf is difficult, because of the in- 20 accessible nature of the abutting surfaces, inattention along this line is all the more noticeable on the part of garage mechanics.

In view of the above, I have devised a 25 lubricating system for springs which provides a new construction in connection with leaf springs, whereby oil will readily flow between the abutting surfaces of the various leaves and be distributed over the entirety of such surfaces.

30 A further object of my invention is the provision of an oiler which provides for the initial introducing and distributing of the lubricating medium for the leaves; and, finally, I provide, in combination with such 35 oiler, an arrangement whereby leakage is eliminated and the same is always maintained in applied position.

With these objects in view, reference is had to the accompanying sheet of drawings 40 which embody one practical form of construction of my invention, and in which—

Figure 1 is a side elevational view of an ordinary elliptical leaf spring with my oiler applied thereto;

45 Fig. 2 is an enlarged sectional side elevation of the oiler as shown in Fig. 1;

Fig. 3 is a bottom plan view taken along the line 3—3 of Fig. 2;

Fig. 4 is a sectional view along the line 50 4—4 of Fig. 1;

Fig. 5 is a sectional end elevation along line 5—5 of Fig. 2; and

55 Fig. 6 is a top plan view of the top leaf and of the elliptical spring as disclosed in Figs. 1 and 2.

In these various views, the same reference numerals designate the same parts, and 1 refers to the body of an elliptical leaf spring, 2 to the top leaf thereof. Extending through all of these leaves is an oiler 3 located approximately intermediate the two shackles 4 securing the ends of the spring 1 in place.

The oiler 3 includes a body 5 formed with a head 6 at one of its ends and screw 65 threaded, as indicated at 7, at its outer end. A screw-threaded opening 8 is formed in the head 6, and channels 9 extend from such opening parallel to the longitudinal axis of the oiler 3 and along the outer surface of the body 5. An oil cup 10 is mounted in the screw-threaded opening 8 and communication between these two parts is afforded by a passage, such as 11.

70 The leaves of the body portion 1, as well as the top leaf 2, are formed with grooves 12 extending longitudinally of such leaves and terminating adjacent their end portions. It will now be noticed that the channels 9 afford communication between the oil cup 80 10 and the grooves 12 of the individual leaves, and it will consequently be appreciated that oil in the cup 10 may flow through the passage 11 and be distributed 85 between the leaves by means of the channels 9 which will conduct such oil into the grooves 12.

It will now be understood that if the body 5 should turn, the channels 9 would not align with the grooves 12, and consequently 90 the apparatus would not function properly. To eliminate this defect, I render the body of the bolt 5 incapable of turning by providing, for instance, the underside of the head 6 with lugs 13, which engage notches 95 14 formed in the upper face of the leaf 2.

It will, of course, be appreciated that leakage of oil might result between the oiler 3 and the lowermost leaf of the body 1, and for this reason I have provided the body 5 100 of the oiler 3 with screw threads, as aforementioned and indicated by 7, upon which screw threads is mounted a nut 15. Interposed between the nut and the underside of the lowermost leaf included in the body 1, 105 is a felt washer 16 and an iron washer 17.

The nut 15 is split, as indicated at 18, and is provided with a screw 19 extending across said split portion, by means of which the threads of the nut 15 may be drawn closer 110

together and so distorted as to prevent the accidental removal of this nut after the same has been properly positioned.

Between the shackles 4 a secondary oiler 5 may be optionally arranged, such secondary oiler including a bolt 20 formed with grooves 21 extending longitudinally of its body portion and upon the exterior surface of the same, and a head 22 provided with 10 channels 23 affording communication between the outer atmosphere and the grooves 21. The lower end of the bolt 20 is formed with screw threads, such as indicated by the reference numeral 24, upon which is 15 mounted a nut 25 split as at 26, and, in fact, corresponding in every particular to the nut 15 illustrated in Fig. 2, even so far as being provided with an iron washer 17 and a felt washer 16 is concerned. Similar in every 20 respect to the conventional spring mounting, the end of one of the springs 1 extends around the bolt 20, and such bolt is carried by shackles 4, as indicated in Fig. 1.

In operation it will now be understood that 25 upon the leaves 1 being assembled, so that the openings through their body portions are in alinement one with the other and form a continuous passage, the screw-threaded end of the bolt 5 is inserted through such passage 30 and the felt washer 16, iron washer 17, and nut 15, applied to the screw-threaded end 7,

care being taken that the lugs 13 enter the notches 14 so as to insure proper registering of the grooves 9, with respect to the grooves 12, and, in consequence, a good distribution of oil over the lower and upper surfaces of the leaf springs 1 and 2. After the nut has been applied in this manner, the screw 19 is tightened down and accidental removal of the nut is thereby prevented. Further, by the provision of the grooves 12 upon the underside of the leaves 1 and 2, a much better distribution of oil is effected, it being understood that capillary action will soon work the oil properly from the groove 12 between the contracting surfaces of the leaves 1 and 2. 35 40 45

It is to be appreciated that such modifications as I may desire to make may be manufactured without departing from the scope 50 of my invention.

Having now described my invention, what I desire to claim is:

A spring oiler, including a leaf spring formed with an opening in its individual 55 leaves, an oil plug positioned within such opening, a nut engaging the lower end of the plug, and a felt and an iron washer interposed between the upper face of such nut and the underside of the lowermost leaf.

GEORGE A. TUTTLE.
